UNITED STATES PATENT OFFICE.

ALEX E. AMANS, OF SEATTLE, WASHINGTON.

SEPARATING OIL-CANS.

1,320,356.

Specification of Letters Patent. Patented Oct. 28, 1919.

Application filed January 16, 1919. Serial No. 271,478.

To all whom it may concern:

Be it known that I, ALEX E. AMANS, a citizen of the United States, residing at Seattle, in the county of King and State 5 of Washington, have invented certain new and useful Improvements in Separating Oil-Cans, of which the following is a specification.

This invention relates to an improvement 10 in machines for separating metallic cans from the wooden receptacles or boxes in which they are shipped.

It is customary to protect metallic containers of this type in wooden cases, and 15 to save shipping space and for other commercial reasons it is usual to pack two such metallic cans or containers in one wooden case.

These wooden cases are made to just receive 20 the metallic cans, and in order to free the cans it has heretofore been necessary to practically destroy the wooden case.

The main object of the present invention is, therefore to provide a machine for 25 removing the metallic cans from such wooden cases, with the destruction of as little of the wooden case as possible, and with the minimum of labor and expense in the operation.

30 The invention will be described in the following specification, with particular reference to the accompanying drawings, in which:—

Figure 1 is a plan of the improved machine, the top or cover section being removed.

Fig. 2 is a side elevation of the same, with the top section in place and partly broken out.

40 Fig. 3 is an end elevation of the machine viewed from the discharge end.

Fig. 4 is a transverse section on line 4—4, Fig. 1.

Fig. 5 is a perspective view of a cutting 45 or splitting device, and,

Fig. 6 is a perspective view of the hammer operating trip.

The improved machine comprises a main frame 1, made up of base stringers 2, and 50 table stringers 3 supported from the base stringers by uprights 4.

Arranged between the table stringers 3, at each end of the machine, are belt rollers 5, over which endless belts 6 are adapted 55 to travel. These belts, which aside from the details noted, may be of any structure, are

spaced apart to just receive the side edges of the wooden case, shown at 7, in which the cans 8 to be removed, are packed.

The belts when so arranged provide a 60 central open space 9, somewhat less in width than that of the wooden case 7, but sufficient in width to permit the cans 8 to pass therethrough. Flights 10 are arranged on the belts, for compelling travel of the box 65 with the belts.

At the entrance end of the machine, and to one side thereof, is arranged a revolving upright shaft 11, having radial arms 12 at the upper end thereof, to engage and initially move the wooden case and contained cans onto the belts. If desired, and as preferred, a feeding means may be provided for delivering the filled cans to the machines, such means being here shown as suitably 75 driven and supported belts 13, having flights 14, and on which the filled cases are placed by hand for delivery, to the machine. This initial feeding means is preferred, as thereby the cases may be delivered to the 80 machine in properly timed order as will be later apparent.

The full length of the machine is protected above the table stringers 3 by an inclosing section or cover 15, having side 85 walls and a top. The side walls are spaced apart to just permit the case to move therethrough, whereby the case is guided and held true in travel.

Splitting knives 16 and 17 are arranged 90 in the path of travel of the case, an upper set 16 being secured to the top of the cover section 15, and the lower set 17 secured to a cross bar 18 arranged on the main frame. The knives 16 and 17, which are equal in 95 cutting depth to the thickness of the top and bottom boards of the wooden case 7, are designed as the case is fed forward, to split the top and bottom of such case into narrow strips. The usual metallic corner 100 binders of the case are also cut by the knives.

A clearing member is arranged in rear of the splitting knives, such clearing member comprising a bar 19, secured to the 105 frame and arranged in the path of the bottom of the case, and a similar bar 20 secured to the cover and arranged in the path of travel of the top of the case. Springs 21 are arranged in advance of the bar 19 110 to initially receive the impact and cushion the same.

The wooden cases in their delivery to the belt 6 are timed so that each case will be taken up by the flights 10, and the cases forced past the knives 16 and 17, after 5 which the clearing members serve, as the split top and bottom of the case reach the same, to clear these parts from the case. All nails holding these parts are of course removed at this operation such nails 10 remaining in the split top and bottom and being drawn from the sides and ends upon the removal of the split portions.

The case now has the sides and end only with the contained cans. In rear of the 15 clearing members is arranged the can remover, comprising a hammer head 22 of a size to fit in the case to engage both cans therein. This hammer head is carried on an arm 23, pivotally supported on a side post 20 24, and is operated through a suitably driven wheel 25, having cam projections 26.

These projections successively engage beneath a lug 27, depending from the arm 23, so that the hammer head is raised and allowed to drop at regularly timed intervals. 25

As the open case is delivered beneath the hammer head, the latter just previously raised, is permitted to drop, forcing the cams from the case onto a suitable bed 30 through the opening 9 in the belt 6.

The cans are thus removed from the cases in a continuous simple operation, and the sides and ends of the wooden cases are kept together and in original shape for re-use. 35

The case is next discharged from the leading end of the belts 6.

Claims:—

1. A machine of the class described, comprising an endless conveyer for the cases, 40 means arranged in the path of travel of the case to split the top and bottom portions thereof, means to remove the split portions, and means to force the contents of cases therefrom.

2. A machine of the class described, comprising endless conveyers to carry the cases and spaced apart at less width than the cases, means for splitting the tops and bottoms of the cases, means for subsequently 50 interrupting the travel of the split portions of the cases to force such split portions between the conveyers, and means for finally forcing the contents of the cases between the conveyers.

3. A machine of the class described, comprising a case, conveyers spaced apart and above which a case is positioned, a cover inclosing the conveyer and guiding the cases in travel, upper and lower splitting knives 60 arranged in the path of travel respectively of the top and bottom sections of the case, means operating subsequently to the knives

for removing the split portions of the case, and a hammer operating through the open case to force the contents thereof between 65 the conveyers.

4. A machine of the class described, comprising a case, spaced conveyers above which a case is positioned, a cover inclosing the conveyer and guiding the cases in travel, 70 upper and lower splitting knives arranged in the path of travel respectively of the top and bottom sections of the case, means operating subsequently to the knives for removing the split portions of the case, a hammer 75 to force the contents of the case between the conveyers, and a cam wheel for periodically raising the hammer and freeing the same for gravitational movement.

5. A machine for removing cans from 80 wooden shipping cases, comprising a frame, endless conveyers operating thereon and spaced apart of less width than that of the case, means on the conveyers to move a case therewith, a cover above the conveyer to 85 accurately guide the case in travel on the conveyer, splitting knives for the top and bottom sections of the case and supporting respectively by the cover and frame, clearing bars carried by the cover and frame to 90 engage the split top and bottom of the case in the travel of the case and force such split portions between the conveyers, and a hammer operating through the case following the action of the clearing bars to force the 95 contained cans between the conveyers.

6. In an article of the class described the combination of a frame work, conveyers upon the same adapted to convey wooden can containers, said conveyers being spaced 100 apart a distance less than the width of the containers, a chute upon the frame work which just allows the container to pass therethrough, a set of knives carried by the frame, and a similar set of knives carried by 105 the chute, the said knives being of substantially the same width as the top and bottom boards of the container, lugs on the conveyers to prevent retrograde movement of the containers, a cross-piece on the frame and springs on the cross-piece against which springs the said containers are adapted to contact, a cross piece on the chute, the said cross-pieces being of substantially the same thickness as the top and bottom boards of 110 the container, whereby when the container is forced against the said cross-pieces the top and bottom thereof will be forced from the container, a trip hammer, and means for operating the hammer to deliver a blow 115 120 from the same upon the exposed cans.

In testimony whereof I affix my signature.

ALEX E. AMANS.
